UNITED STATES PATENT OFFICE.

JOHN A. RENNIE, OF DELAWANNA, NEW JERSEY, ASSIGNOR TO STAR SEAL COMPANY,
A CORPORATION OF NEW YORK.

BOTTLE-SEAL.

982,875.

Specification of Letters Patent. Patented Jan. 31, 1911.

Application filed June 27, 1908. Serial No. 440,664.

To all whom it may concern:

Be it known that I, JOHN A. RENNIE, a subject of the King of England, residing in Delawanna, county of Passaic, State of New Jersey, have invented certain new and useful Improvements in Bottle-Seals, of which the following is a specification.

My invention relates to bottle seals of the class known as outside seals, in which an inverted metal cup is crimped on the top of the bottle around a bead on the outside of the neck. Usually these seals are provided with a cork disk on the inside to effect the actual sealing of the bottle when held down by the crimped cap. The objection to seals of this general character is that a special form of implement is required to remove them from the bottle in order to get at the contents thereof, and it is the object of my invention to provide means whereby the seal may be removed by almost any convenient implement, such as a fork, or a lead pencil, or the like. In order to accomplish this I attach to the seal by any convenient means a loop of wire or strong cord in such manner that the same will project above the top of the seal and permit of the insertion of a variety of implements, so as to give the necessary leverage to pull off the seal and open the bottle. In the preferred form of construction, I lay the wire between the cork disk and the cap and near the circumference of the disk, and allow the loop to project out beyond the cap at any convenient point. The necessary pull to remove the seal will draw the base of the loop against the sharp edge of the cap, and as the wire is doubled back upon itself at this point there is practically no tendency for it to slip. Furthermore, when the seal is in position on the bottle, it is held down under considerable pressure, due to the force of the machine used in applying the cap, and this pressure also serves to prevent slipping.

Referring to the drawings, Figure 1 is a perspective view of the neck portion of a bottle having my improved seal applied thereto; Fig. 2 is a central vertical cross section of the same; and Fig. 3 is a horizontal cross section on the line 3—3 of Fig. 2.

A is the neck of the bottle on the top of

which is crimped the seal B in the usual manner. This seal is composed of the holding member b, which is usually made of metal, and the sealing member b', which is usually made of cork. When the seal is applied, it is pressed down on top of the bottle, so as to force the cork disk slightly into the mouth of the bottle, and then the depending edge of the holding member is crimped around the bead of the bottle.

C is a strand or a number of strands of wire, cord or equivalent material, the ends of which are twisted together so as to make an endless strand. This wire or cord C is laid between the cork disk b' and the metal cap b around the outer periphery of the disk before the seal is applied. A portion of it projects outside of the seal so as to form the loop D. When the seal is applied, the wire is in the position shown in Figs. 2 and 3, and for convenience in handling and shipping the loop is turned down along the neck of the bottle, as shown. For the purpose of removing the cap, the loop is bent up so as to project above the top of the seal, and any small implement is inserted through the loop so as to bear on the opposite edge of the seal and form a lever to pull the seal off. I prefer to have the twisted ends of the wire outside of the seal so that their added thickness will not interfere with the tight sealing of the bottle.

Having described my invention, what I claim is:

1. In a bottle seal, the combination of a metal cap, a compressible sealing disk, and a wire laid between said disk and said cap around the rim of said disk, and formed into a loop projecting outside of the metal cap.
2. In a bottle seal, the combination of a metal cap, a compressible sealing disk, and a wire laid between said disk and said cap around the rim of said disk in the zone of greatest pressure, and formed in a loop projecting outside of the metal cap.

In witness whereof I have hereunto set my hand, this 26th day of June, 1908.

JOHN A. RENNIE.
